UNITED STATES PATENT OFFICE.

EUGEN SANDOW, OF LONDON, ENGLAND.

EXERCISING-MACHINE.

SPECIFICATION forming part of Letters Patent No. 588,017, dated August 10, 1897.

Application filed March 13, 1897. Serial No. 627,402. (No model.)

To all whom it may concern:

Be it known that I, EUGEN SANDOW, a subject of the Emperor of Germany, residing at London, England, have invented a new and useful Improved Apparatus for Promoting Muscular or Physical Development, of which the following is a specification.

The object of this invention is to construct a simple, economical, and efficient form of "exerciser" for promoting the muscular or physical development of the human frame; and the invention will be readily understood from the following description on reference to the accompanying drawings.

15 Figure 1 is a side view, and Fig. 2 a face view, of an apparatus for the development of muscles, made according to my invention. Figs. 3 and 4 show modifications thereof.

According to my invention I fix in a wall 20 *a*, as shown, or in a post, door, ceiling, or other convenient position two strong metal hooks *b* or other similar permanent fastenings, say about six feet apart, more or less. To these I attach by one end two strong india-rubber or other springs *c* of, say, about 25 two feet six inches long, or other desirable length, and I connect the other ends of these springs *c* together in the center between the two fixed hooks by a loop *d*, formed of cord, 30 canvas, or other suitable material of such a length that the two springs *c* above named shall be held in tension counteracting each other with the loop *d*, of canvas or cord or its equivalent, against the wall at a suitable 35 height, say about the shoulders, or somewhat lower, or instead of the loop *d* I may use more than one loop linked together, as seen dotted at Fig. 4. To this loop or other equivalent device at *d* I attach two other india-rubber 40 springs forming elastic cords *e e*, at the outer end of each of which is a handle *ff*.

In some cases more than two fixed hooks *b* may be used, as seen at Fig. 3, equidistant from and connected to a centrally-placed loop 45 or equivalent device *d* by means of springs *c*, the effect being that as the center of the wall-spring so formed is pulled from the wall the

springs *c* will tend to strengthen the resistance and equalize the tension in certain movements, which in the case of the springs only 50 fixed in one line, say perpendicularly, is not experienced. The wall-springs, as before explained, must be stretched to enable them to be fixed to the hooks.

The exercise is given by pulling at the handles *ff* either singly, alternately, or both together, so as to draw the loop or its equivalent at *d* away from the wall or otherwise displace the same, (see dotted lines, Figs. 1 and 2,) which movement is resisted by the springs *c*. 55 60

When it is required to make the exercise more severe, this may be done by hooking on or otherwise attaching one, two, or more additional springs *c'* (see Fig. 4) between the loop or band or its equivalent at *d* and the 65 fixed hooks or fastenings *b*, so that the same exerciser can be adapted to give any desired amount of resistance, either light, medium, or heavy, by simply hooking on or removing the corresponding number of springs. The 70 "pull" may be given either horizontally, diagonally, upward, or downward, and either forward or backward, according to the effect desired to be produced, and without creating any extra tension or strain which results when 75 the handle-springs are fixed to or pass through fixtures to the wall or other part.

I claim as my invention—

The herein-described apparatus for muscular and physical development, consisting of a 80 plurality of handles, elastic cords connected thereto, a central device to which said cords are connected, and counteracting-springs connected to and supporting said central device, the said springs being fastened at their outer 85 ends to fixtures, substantially as described.

In testimony whereof I have signed my name to this specification in the presence of two subscribing witnesses.

EUGEN SANDOW.
